TUBULAR AIR PREHEATER FOR STEAM
GENERATOR UNITS AND THE LIKE

John V. Pyle, Briarcliff Manor, N. Y., assignor to
Kennedy-Van Saun Mfg. & Eng. Corp., New
York, N. Y., a corporation of Delaware

Application September 4, 1946, Serial No. 694,792

10 Claims. (Cl. 257—224)

1

This invention relates to improvements in tubular air preheaters such as the preheaters used in connection with large steam generator units.

In large steam generator units the air preheater is usually built as a part of the setting and so positioned that the hot combustion gases from the upper part of the unit pass over into the tubes of the air preheater and pass downwardly through the tubes of the air preheater in heat exchange with air passing around the tubes, which is preheated for use in the generator. It has been found expedient in the case of large steam generators to build the air preheater in two sections one above the other. In such practice each section is constructed with vertically arranged tubes 20 feet or more in length, with their ends rolled or otherwise secured in tube sheets. The two sections are commonly constructed alike and one section set above the other in spaced relation so that it is possible for man to get in and work between the two adjacent sections.

One of the difficulties in such constructions is that in order to make repairs in the lower section of the air preheater it is necessary to remove the tubes in the upper section, that is in order to remove tubes in the lower section. It has also been found that most of the tube difficulties arise in connection with the lower section. Some of the reasons for this are not clearly understood. For one thing the tubes of the lower section require much more frequent cleaning, to remove soot, than the upper tubes, as well as much more frequent repair and replacement.

The primary object of the present invention therefore is to provide an improved tubular air preheater which will be free of the difficulties and disadvantages referred to above.

Another object of my invention is to provide an improved air preheater for use in connection with large steam generators which is easy to repair and maintain.

I have discovered that most if not all of the difficulties referred to may be eliminated if the lower tube section is constructed of tubes of smaller diameter than those of the upper tube section. In the preferred form of my invention I provide an air preheater as for example for a large steam generator unit with upper and lower tube sections. The lower tube section includes the same number of tubes as the upper tube section, but they are of a diameter such that tubes of the lower section may be passed through the tubes of the upper section. In this connection I arrange the sections so that the tubes of the lower section are directly below the tubes of the

2

upper section so that the smaller lower tube may be moved upwardly through the corresponding tubes of the upper section, when repairs or replacements are made.

5 An air preheater constructed in accordance with the features of my invention has been found to have a number of advantages over preheaters made in accordance with known practices. For example, I have found that much less repair or 10 replacement of lower tubes is necessary in the new construction and that a greater efficiency is achieved in the transfer of heat from furnace gases to the air being preheated. Much less cleaning of the lower tube section has also been 15 found necessary. This increase in efficiency is quite unexpected since the use of smaller diameter tubes in the lower section of the air preheater reduces considerably the heat exchange surface between the combustion gases and the 20 air being preheated. However, it appears that the smaller tubes in the lower section have the function of keeping up a relatively high combustion gas velocity which results in the maintenance of cleaner tubes and a higher rate of heat transfer than in the case of tubes of the same diameter as those in the upper tube section.

25 My improved tubular air preheater includes other features, objects, and advantages which will be readily understood from the following detailed 30 description thereof taken in connection with the accompanying diagrammatic drawings forming a part of this application.

In the drawings:

Fig. 1 is a broken vertical sectional view showing 35 a portion of a large steam generator unit provided with an air preheater constructed and arranged in accordance with the features of my invention.

Fig. 2 is a broken vertical sectional view showing 40 a portion of the apparatus illustrated in Fig. 1 on an enlarged scale.

Fig. 3 is a broken horizontal sectional view taken on the broken line 3—3 of Fig. 2.

Fig. 4 is a view similar to that of Fig. 2 illustrating the method of removing and replacing 45 tubes of the lower tube section of the heater.

Fig. 5 is a broken elevational view of the tubular preheater shown in Fig. 1, looking from the left.

Fig. 1 of the drawings shows a portion of a 50 large steam generator unit mounted in a building structure having a side wall 10 and a roof 12. The portion of the generator as shown includes a water and steam drum 14, in the upper part of the setting, and a lower drum 16, which are connected by long steam generating tubes 18.

The steam generator includes a firing chamber and other conventional elements from which the combustion gases pass upwardly through a chamber 20 to heat the tubes 18 mounted in the furnace. These gases pass around the upper ends of the tubes 18 into a tubular air preheater which may extend substantially across the generator and which, as shown, comprises an upper tube section or bank 22 and a lower tube section or bank 24. As an example, these sections may be 20 feet or more in height.

The tube sections 22 and 24 are mounted in the steam generator setting in the usual manner and carried by the usual steel framework structure as, for example, by steel beams 26. The tubular air preheater is enclosed by the refractory walls as indicated and the two sections are mounted one above the other with an intervening space or chamber 28 suitable for a man to enter for inspection, replacement, or for installation work. The side of the chamber 28 is provided with a row of refractory lined doors 30 which are removably mounted in the setting. At the top of the setting above the tube section 22 a row of horizontal doors or covers 32 are provided so that the upper portion of the section 22 will be accessible from above. The doors or covers 32 may be lifted in and out of the setting by suitable crane means or by a block and tackle.

The combustion gases from the chamber 29 which pass over into the tube bank 22 pass downwardly through both sections of the tubular air preheater and out through ducts 34 and 36 to a stack or exhaust fan not shown. Any dust settled out of the gases leaving the section 24 is removed through a dust trap 31. The air to be preheated is introduced around the tubes of the section 24 at the bottom of the setting and passed upwardly around baffles 38, through a by-pass duct 40 shown in Fig. 5 and then upwardly around the tubes of section 22. Baffles 42 causes the air to pass in a zigzag path across the tubes of the preheating section 22 until it reaches the top of the section 22 where the hot or preheated air is discharged through a duct 44, and conducted to the combustion chamber of the generator unit by means not shown.

An important feature of my invention as pointed out above is the construction of the preheater section 22 with one size of tubes and the preheater section 24 with tubes of a smaller diameter. It will be noted that the section 22 includes upper and lower tube sheets 46 carrying regularly spaced heat exchange tubes 48. The lower preheater section 24 comprises upper and lower tube sheets 50 in which are mounted tubes 52 having an outside diameter slightly less than the inside diameter of the tubes 48, for example, the tubes 52 may be one size smaller than the tubes 48. This relationship is illustrated in enlarged scale in Figs. 2 and 3. The tubes 48 and 52 may be rolled in their respective tube sets or welded therein. It will be noted that in accordance with the showing in Fig. 3 the tubes 52 are mounted directly below and axially in line with the tubes 48.

In most generator installations the conditions are such that the tubes in the lower preheater section require more frequent replacing than the tubes in the upper section. In the present instance, this replacement of the tubes in the lower preheater section is made rather simple since each lower tube may be removed directly through one of the tubes 48, that is, the tube directly above. Fig. 4 of the drawings illustrates the manner in

which this may be readily accomplished. If an inspection of the tubes 52 shows that some of them must be removed, they are cut away or otherwise removed from the tube sheets 50 after which a rope 54 is lowered through the tube 48 directly above and also through the tube 52 to be removed. A knot or other suitable attachment 56 is applied to the end of the rope below the tube 52 and then the latter is raised through the tube 48 by the rope 54 which may be passed through a sheave 58 as indicated. A new tube may be inserted in its proper place in the tubular section 24 by following the foregoing procedure in reverse. If the rope 54 is a metal rope or cable, it may be used for holding the new tube while it is spot welded in place. In making repairs the closures 30 and 32 are removed and a man enters the space below the section 24, through trap 37 or an end door 60 as shown in Fig. 1.

Many of the large steam generator installations are housed in buildings so arranged that the use of vertically spaced air preheater sections of the type of sections 22 and 24 are highly desirable from the standpoint of repair and replacement of parts. While it is possible in making the original installation to install sections 22 and 24 as units, the section 24 being installed first, it is not usually possible in view of all the other equipment such as flue ducts, air ducts, and various auxiliary units, to remove a section as a whole. The present invention therefore provides a novel construction and procedure by which repairs and replacements of tubes in such a tubular air preheater may be made. The improved construction not only facilitates repairs to the lower section of the air preheater, but also provides a preheater which is more efficient than present preheaters and which, because of the use of smaller tubes in the lower section, is less expensive.

From the foregoing description it will be understood that certain minor changes in the construction and arrangement of the various parts may be made without losing any of the advantages of the apparatus. Such changes are contemplated as coming within the spirit and scope of the appended claims.

What I claim as new is:

1. In a tubular air preheater of a steam generator unit adapted to receive hot combustion gases and air to be preheated thereby, an improved air preheater comprising vertically arranged tube sections each of which includes a bank of vertically mounted tubes for the passage of hot combustion gases, said tube sections being spaced apart to provide access for repairs between sections and arranged so that the hot combustion gases from the upper tube section pass downwardly through the tubes of the lower tube section, and the tubes of the lower tube section having an outside diameter slightly smaller than the inside diameter of the tubes of the upper section, whereby the tubes of the lower section may be removed through the tubes of the upper section for repairs and replacements.

2. An air preheater as defined by claim 1 in which the tubes of the lower tube section are mounted in axial alignment with tubes of the upper tube section.
3. An air preheater as defined by claim 1 in which the air preheater is mounted within the steam generator setting and includes a removable closure above the upper tube section, a removable closure for the space between the tube sections,

and a removable closure for the space below the lower tube section.

4. An air preheater as defined by claim 1 in which means is provided for passing air to be preheated first around the tubes of the lower tube section and then around the tubes of the upper tube section.

5. In a tubular air preheater for preheating air by heat exchange with hot combustion gases, a pair of upright tubular heat exchange sections mounted one above the other and each including a bank of long vertically arranged tubes, the tubes of the lower section having an outside diameter slightly less than that of the inside diameter of the tubes of the upper section and being arranged with their axes substantially coincident with the axes of the tubes of the upper section, whereby tubes of the lower section may be passed through tubes of the upper section.

6. A tubular heat exchange unit comprising upper and lower tube banks comprising upwardly extending tubes, means for mounting one bank of tubes directly above the other and in spaced relation with respect thereto, the tubes of the lower bank being mounted below and in line with tubes of the upper bank and having an outside diameter slightly smaller than the inside diameter of the tubes of the upper bank, whereby tubes of the lower bank may be moved through tubes of the upper bank.

7. In a tubular heat exchange unit comprising tubular sections arranged one above the other and each having vertically arranged tubes, the tubes of the lower section being of an outside diameter slightly smaller than the inside diameter of the tubes of the upper section and arranged with their axes substantially coincident with the axes of the tubes of the upper section whereby tubes to be replaced in the lower section may be passed respectively through vertically aligned tubes of the upper section.

8. A tubular heat exchange apparatus including vertically arranged tubular sections in which the tubes of the upper section are mounted in axial alignment with the tubes of the lower section, and the tubes of the upper section having

an inside diameter slightly greater than the outside diameter of the tubes of the lower section, means extending through a tube of the upper section adapted to be attached to a tube of the lower section, and means for elevating the tube to which said means is attached through a tube of the upper section.

9. A tubular heat exchange apparatus as defined by claim 8 in which the means extending through an upper tube comprises a rope.

10. In a tubular air preheater adapted to receive air to be preheated and hot combustion gases for effecting preheating, the improvement which comprises an upright tubular air preheater including means at its upper end for receiving hot combustion gases, means at the bottom of the preheater for discharging hot combustion gases, the tubular air preheater including vertically spaced banks of vertical tubes the ends 15 of which are mounted in tube sheets, the tubes of the lower bank having an outside diameter slightly smaller than the inside diameter of the tubes of the upper tube bank and being mounted with their axes aligned respectively with the axes 20 of tubes of the upper tube bank, a removable closure above the upper tube bank for access thereto, and a removable closure for the space between the tube banks for access thereto.
